UNITED STATES PATENT OFFICE.

FRED O. REHFIELD, OF NEWARK, NEW JERSEY.

EMBLEM AND PROCESS OF MANUFACTURING THEREFOR.

Application filed April 13, 1927. Serial No. 183,599.

The present invention relates to an improved method or process of manufacturing emblems for the purpose of providing transparent indicia such as letters to be lit up at 5 night so that names, sayings, and the like may be readable in display windows and like places.

An important object of the invention lies in the provision of an article and a process 10 for manufacturing the same whereby cheapness and speed in manufacture are obtained and efficiency and reliability in the article are attained.

With the above and other objects in view 15 as will appear as the description proceeds, the invention resides in certain novel features of construction and in the process of manufacture thereof as will be hereinafter more fully described and claimed.

20 In the drawing:

Figure 1 is a plan view of the article after the second step in the process of manufacture,

Figure 2 is a transverse section there- 25 through taken substantially on the line 2—2 of Figure 1,

Figure 3 is a bottom plan view of the article after the third step,

Figure 4 is a top plan view of the article 30 after the fourth step,

Figure 5 is a sectional view taken sub- 35 substantially on the line 5—5 of Figure 4,

Figure 6 is a plan view of the finished article and

Figure 7 is a sectional view taken there- 40 through substantially on the line 7—7 of Figure 6.

The first step in this improved process resides in the laying of a piece of cloth or fabric on a table or the like, the laying of a 45 piece of isinglass on top of the cloth or fabric and then the laying of a piece of leatherette or the like on top of the isinglass or the like. The second step resides in embroidering a frame bead 5 around the outer surface of the leatherette 6, and through the isinglass 7 and the cloth 8. The third step consists in cutting out the cloth or fabric lying inside the embroidering bead 5 as is illustrated in Figures 6 and 7. The fourth step resides in the embroidering of each letter 50 separately on the outer edge and through the leatherette and isinglass as is indicated at 9. The fifth and final step consists of cutting 55 out the forms of the letters from the leather-

ette so as to produce the article illustrated in Figures 6 and 7 of the drawings.

The purpose of the cloth or fabric is to form a frame, thereby holding the isinglass and leatherette in place, so that the letters 60 may be cut out from the leatherette. Each letter and each frame is separately 65 embroidered, and by pulling one stitch from the completed work, the whole frame or letter will immediately pull out. By thus taking out the embroidery on the outer frame, the isinglass and leatherette can be lifted from the cloth frame, and a new set of letters may be made up on other isinglass and leatherette and put on the old frame. The use of 70 the embroidery stitch as described not only affords ease of assembly and ease of disassembly as explained, but functions as a bead to accentuate the letter so as to make the same 75 very distinct and easily read. It is quite obvious that other equivalent materials may be used than those specifically mentioned, and it also will be apparent that instead of 80 letters, figures, numerals, and the like may be embroidered and cut out as described.

The present particular embodiment of the invention has been disclosed in detail merely by way of example since in actual practice it attains the features of advantage enumerated as desirable in the statement of the invention and the above description. It is apparent, however, that changes in the details of construction, in the material, in the combination and arrangement of parts, and the specific steps of the process may be resorted 85 to without departing from the spirit or scope of the invention as hereinafter claimed or sacrificing any of its advantages.

Having thus described my invention, what I claim as new is:

1. As a new article of manufacture, a device of the class described formed from a sheet of cloth, a sheet of isinglass on the cloth, and a sheet of leatherette over the isinglass each of a contrasting color, stitching holding together the three sheets, stitching of a contrasting color from the sheets outlining indicia on the leatherette and isinglass, said leatherette being provided with an opening within the confines of the last mentioned stitching and said cloth being provided with an opening within the confines of the first mentioned stitching.
2. An article of manufacture formed from a plurality of sheets of flexible material and

including a sheet of transparent material interposed between sheets of opaque material, each of said sheets being of a contrasting color, stitching securing the sheets together and defining the border of the transparent sheet and one of the opaque sheets, said other opaque sheet having an opening in the border, stitching of a contrasting color arranged on the surface of the first named

opaque sheet and extending through the 10 transparent sheet and forming an outline for indicia of predetermined design, said first named opaque sheet having an opening within the confines of the last named sheet and registering with the opening in said 15 other opaque sheet.

In testimony whereof I affix my signature.
FRED O. REHFIELD.
